WINDOW-SASH LOCK.

1,110,007.

Specification of Letters Patent.

Patented Sept. 8, 1914.

Application filed May 20, 1914. Serial No. 839,885.

To all whom it may concern:

Be it known that I, MARK NOBLE PUTNAM, a citizen of the United States, residing at Wichita, in the county of Sedgwick and State of Kansas, have invented a new and useful Window-Sash Lock, of which the following is a specification.

The invention relates to improvements in window sash locks.

10 The object of the present invention is to improve the construction of window sash locks and to provide a simple, practical, and inexpensive window sash lock of strong and durable construction, adapted to be readily applied to a window and capable of locking the sashes either in their closed position or in an open position for ventilation.

15 A further object of the invention is to provide a window sash lock of this character, equipped with a pair of bolts, one of the bolts being arranged to lock the upper and lower sashes of a window together, and the other being movable into and out of engagement with the window frame or casing, 20 so as to lock the upper and lower sashes rigid with the same.

25 Another object of the invention is to provide a sash lock adapted to lock the lower sash to the window frame or casing at any point, either open or closed, while permitting an adjustment of the upper sash, and equipped with means for preventing a partial movement of the bolt which engages the window frame or casing, so that it will 30 be necessary to rotate the knob of an operating bolt to the right sufficiently to completely shoot the bolt which locks the lower sash and engages such bolt with the window frame or casing before the operating 35 bolt can be engaged with the upper sash, thereby avoiding any liability of accidentally leaving the lower sash unlocked.

40 With these and other objects in view the invention consists in the construction and 45 novel combination of parts hereinafter fully described, illustrated in the accompanying drawing, and pointed out in the claims here-to appended, it being understood that various changes in the form, proportion, size 50 and minor details of construction, within the scope of the claims, may be resorted to without departing from the spirit or sacrificing any of the advantages of the invention.

55 In the drawing:—Figure 1 is a front elevation of a window sash lock constructed

in accordance with this invention, and shown applied to a window, the window frame or casing and the metallic keeper strip thereof being in section. Fig. 2 is 60 a vertical sectional view taken at right angles to Fig. 1. Fig. 3 is a vertical sectional view on the line 3—3 of Fig. 1. Fig. 4 is a vertical sectional view on the line 4—4 of Fig. 2. Fig. 5 is a horizontal section view. Fig. 6 is a transverse sectional view on the line 6—6 of Fig. 3. Fig. 7 is a detail perspective view of the sliding and rotary operating bolt.

65 Like numerals of reference designate corresponding parts in all the figures of the drawing.

70 In the accompanying drawing, in which is illustrated the preferred embodiment of the invention, 1 designates a casing forming a housing for horizontal bolts 2 and 3, and designed to be secured to and mounted upon the lower sash 4 of a window at the right hand side of the same. The casing, which may consist of a casting or be constructed in any other desired manner, is 75 secured to the lower sash by vertical screws 5 and a horizontal screw 6, but any other desired arrangement of fastening means may, of course, be employed. The vertical 80 screws 5 pierce the casing and are embedded in the top rail of the lower sash, while the horizontal screw passes through a depending lug or ear 7, which fits against the front or inner face of said top rail of the lower 85 sash. The bolt 3, which is movable laterally of the casing 1, is mounted in a transverse bore 8 thereof, while the other bolt 2 is mounted in a bore 9, which intersects the bore 8, the bolt 2 preferably passing beneath the bolt 3.

90 The bore 8 is closed at one end by a wall 10, which forms a stop for the bolt 3 to limit the inward movement thereof, and the latter has a lower recess 11 at its inner or rear portion. The bolt 3 is provided at the recess with teeth 12 forming a rack and meshing with a pinion 13, consisting of teeth or ribs extending longitudinally of the operating bolt 2 and permitting a sliding movement of the latter without becoming disengaged from the rack of the laterally movable bolt 3. The operating bolt is equipped at its front or outer end with a milled head or knob 14, and it is adapted 100 to be rotated to reciprocate the laterally movable bolt 3, to engage the same with a

keeper strip 15 and to retract it from such engagement. The keeper strip 15, which is constructed of suitable metal, is secured to the side of the window frame or casing 16 in the groove or channel provided for the movement of the lower sash, and it is located to one side of the vertical transverse plane of the sash cord, so as not to interfere with the same when the device is applied to a window having its sashes balanced by sash weights. The said keeper strip is provided at short intervals with openings 17, forming sockets to be engaged by the laterally movable bolt 3, whereby the lower sash is rigidly locked to the window frame or casing and held against movement in either direction. The pinion 18 is designed to be of a size so that a complete revolution of the operating bolt will produce a full movement of the bolt 3, either to shoot or reciprocate the same.

The inner or rear portion of the operating bolt is arranged in a rear bore or opening 18, and the said bolt is slideable inwardly and outwardly to engage its rear end with and disengage it from a keeper strip 19, secured to the inner or front face of the right hand side bar or stile of the upper sash 20 of the window. The keeper strip 19, which is provided at intervals with socket openings 21 to receive the operating bolt, may be of any desired length to secure the requisite adjustment of the upper sash. In order to prevent the operating bolt from being reciprocated when the laterally movable bolt is in an intermediate position, the said operating bolt is provided near its inner or rear end with an annular groove 22 in which operates a fixed projection 23, preferably formed by a pin 24 piercing the top of the casing and extending into the portion 22 of the bore which receives the operating bolt. The operating bolt is provided with a cut away portion 25 forming a flat face and located at the said projection 23 when the laterally movable bolt 3 is at the limit of its movement in an outward direction. The cut away portion 25 of the operating bolt 2 permits the latter to be moved inwardly or rearwardly into engagement with the keeper strip of the upper sash, as illustrated in Fig. 3 of the drawings. As the operating bolt 2 must make a complete revolution in one direction to turn the cut away portion to a position opposite the projection 23, it will be impossible to slide the operating bolt 2 until the said laterally movable bolt 3 has been completely moved to its engaging position into the keeper strip 15.

When the bolts are in the position illustrated in Fig. 5 of the drawing, the operating bolt, after the lower sash has been adjusted to the desired position, is rotated to the right to carry the laterally movable

bolt 3 into engagement with one of the sockets 17 of the metallic keeper strip 15. This locks the lower sash to the window frame or casing. The upper sash is then free to move and may, after adjustment, be locked to the lower sash and to the window frame or casing by sliding the operating bolt 2 rearwardly and engaging the same with one of the socket openings 21 of the said upper sash. The lower sash must be first locked to the window frame or casing before locking the upper and lower sashes together, thereby insuring the locking of the lower sash at all times at the desired point, as it is necessary to rotate the knob 14 to the right and force the bolt 3 into engagement with the keeper strip 15 before the bolt 2 can be pushed rearwardly into engagement with the keeper strip 19 of the upper sash. It will be impossible to manipulate the sash lock from the exterior by means of a knife, wire, or other instrument, and surreptitiously open a window, whether the sashes be closed, or partly open for ventilation. The position of the sash lock at the right hand side of the window enables it to be manipulated with the right hand while adjusting the sashes with the left hand, and as it is springless and comprises in its construction only two working parts, it presents a strong and durable construction, and is not liable to get out of order.

The device is applicable to various kinds of windows, whether equipped with sash weights or not, and instead of providing keeper strips, as shown in the drawing, separate rings or socket pieces may be mounted on the upper sash and on the window frame or casing in position to be engaged by the bolts of the sash lock.

What is claimed is:—

1. A sash lock comprising a casing having horizontal bores or openings intersecting each other, a laterally movable slideable bolt mounted in one of the bores or openings and provided with a rack, an operating bolt mounted for sliding and rotary movement in the other bore and provided with a pinion meshing with the rack of the laterally movable bolt, and a fixed projection engaging with the operating bolt to lock the same against sliding movement while the same is being rotated to actuate the laterally movable bolt, said operating bolt having a cut away portion engaging the said projection and permitting a sliding movement of the operating bolt when the laterally movable bolt is at the limit of its movement in an outward direction.

2. A sash lock comprising a casing having bores or openings intersecting each other, a laterally movable slideable bolt mounted in one of the bores or openings and provided with a rack, an operating bolt mounted for sliding and rotary movement

in the other bore or opening and provided with a pinion meshing with the rack of the laterally movable bolt, and means coacting with the operating bolt for locking the same
5 against sliding movement until the said operating bolt, through its rotation, has carried the laterally movable bolt completely to the engaging position thereof, said means permitting a sliding movement of the operating bolt when the laterally movable bolt
10 is in the said engaging position.

3. A sash lock comprising a casing having bores or openings intersecting each other, a laterally movable slideable bolt
15 mounted in one of the bores or openings

and provided with a rack, an operating bolt mounted for sliding and rotary movement in the other bore or opening and provided with a pinion meshing with the laterally movable bolt, and means coacting with the 20 operating bolt for locking the same against sliding movement while it is being rotated to actuate the laterally movable bolt.

In testimony that I claim the foregoing as my own, I have hereto affixed my signature in the presence of two witnesses.

MARK NOBLE PUTNAM.
